UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

SECTIONAL INSULATOR.

1,405,608.

Specification of Letters Patent. Patented Feb. 7, 1922.

Application filed August 3, 1921. Serial No. 489,521.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Sec-
tional Insulators, of which the following is
a specification.

My invention relates to devices for sup-
10 porting and insulating conductors and more
especially to that type of device known as a
sectional insulator for trolley conductors
where a high voltage is used upon the con-
ductors.

15 My invention has for its object the sec-
tionalizing of the trolley conductor and
means for conveying the trolley collector
from one section to the next section across
20 an insulated portion and so arranged as to
give a smooth under-run when the collector
leaves one section and enters the other sec-
tion.

25 My invention consists of a novel construc-
tion, combination and arrangement of the
parts fully described and set forth in the
following specifications shown in the at-
tached drawing.

30 Fig. 1 is a top plan view of my invention
and Fig. 2 is a side elevation of my inven-
tion.

35 My invention consists of an insulating
member 1 made preferably of wood and of
such length and size as to withstand the
voltage between the sections and the me-
chanical stresses impressed upon the frame.
40 To each end of the insulating member is se-
cured a metal end section 2, to which may be
secured the end of the trolley wire compos-
ing the section. The end members 2 are se-
cured to the insulating member 1 by means
of bolts or other fastening devices 3.

45 Between the end members 2 and secured
to the insulating member 1 is a bridging
member 4 overlapping the end members 2.
The ends of the bridging member 4 are up-
turned in order to allow the passage of the
50 collector from the end member to the bridg-
ing member smoothly.

The bridging member 4 is supported
from the insulating member 1 by means of
an insulating member 5 secured to the in-
sulating member 1 by means of the bolt 6.
55 Secured to the insulating member 5 is a

clamping member 7 arranged to be secured
to the bridging member 4 by means of the
screws 8 and to be secured to the insulating
member 5 by means of the bolt 9. The in-
sulating member 1 has the portion 10 cut 60
out to permit the passage of the bridging
member from one side of the structure to
the other.

The bridging member 4 is connected to
one of the end castings electrically by means 65
of the cable 11 which allows the collector to
draw current from one section until it has
passed on to the other section. There is a
very short interval of time when the two
70 sections are electrically connected together,
i. e. when the collector is in contact with
the bridging member and right-hand end
member 2, but as this connection is for only
an instant and the potential of the two sec-
75 tions are not widely different there is no dis-
advantage in this instantaneous connection
but there is the advantage that it practi-
cally eliminates the probability of a very
80 high flash as would be the case if the col-
lector left the live section and passed on to
a "dead" bridging member.

There are modifications which will occur
to those skilled in the art but I do not care
to be limited excepting as set forth in the
claims as follows:—

85 1. A trolley device comprising in combi-
nation an interrupted conductor, insulating
means for holding the terminals of the con-
ductor a fixed distance apart, and means for
guiding the trolley across the break com-
90 prising a bar secured to both sides of the
insulating means and having portions ex-
tend laterally thereof and having the inner
ends of the laterally extending portions con-
nected by a crossover member, the lower 95
surface of the bar being in the same hori-
zontal plane as the lower surface of the
conductor except the outer ends of the bar
which are upturned.

100 2. A trolley device comprising in combi-
nation an interrupted conductor, insulating
means for holding the terminals of the con-
ductor a fixed distance apart, and means for
guiding the trolley across the break com-
105 prising a bar positioned on both sides of the
insulating means, extending laterally there-
of, and rigidly secured thereto and means
connecting the inner ends of the bar.

110 3. A trolley device comprising in combi-
nation an interrupted conductor, insulating

means for holding the terminals of the conductor a fixed distance apart, and means for guiding the trolley across the break comprising a single piece bar positioned on both sides of the insulating means and rigidly secured thereto.

4. A trolley device comprising in combination an interrupted conductor, insulating means for holding the terminals of the conductor a fixed distance apart, and means for guiding the trolley across the break comprising a single bar disposed on both sides of the insulating means and having a diagonally disposed central portion connecting the parts of the bar disposed on opposite sides of the insulating means.

5. A trolley device comprising in combination an interrupted conductor, insulating means for holding the terminals of the conductor a fixed distance apart, and means for guiding the trolley across the break comprising a bar disposed on both sides of the insulating means and having its ends overlapping the spaced ends of the conductor and rigidly secured in position and electrically connected to one of the spaced conductors.

6. A trolley wire device comprising in combination an interrupted conductor, insulating means for holding the terminals of the conductor a fixed distance apart, means for guiding the trolley across the break comprising a bar disposed on opposite sides of the insulating means, said oppositely disposed portions being parallel to the conductor and having the ends overlapping the spaced ends of the conductor and diagonally disposed means bridging the oppositely disposed parallel portions of the bar.

40 7. A trolley device comprising in combination an interrupted conductor, insulating means for holding the terminals of the con-

ductor a fixed distance apart and means for guiding the trolley across the break comprising a bar disposed on both sides of the insulating means, overlapping the ends of the conductor and having its lower surface substantially in the same horizontal plane with the lower surface of the conductor.

8. A trolley device comprising in combination an interrupted conductor, insulating means for holding the terminals of the conductor a fixed distance apart, means for guiding the trolley across the break comprising a single bar having portions positioned wholly on either side of the insulating means and a connecting portion positioned on both sides of the insulating means and means to secure the bar in position.

9. A trolley device comprising in combination an interrupted conductor, insulating means for holding the terminals of the conductor a fixed distance apart, means for guiding the trolley across the break comprising a longitudinally disposed member on each side of the insulating bar and means for guiding the trolley from one of said longitudinal members onto the other longitudinal member without simultaneously engaging the two members.

10. A trolley device comprising in combination an interrupted conductor, insulating means for holding the terminals of the conductor a fixed distance apart, and means for guiding the trolley across the break comprising a member extending from a point approximately opposite the conductor terminal at one end of the device to a point approximately opposite the conductor terminal at the other end of the device and having the ends of the guiding means located on opposite sides of the device.

In testimony whereof I affix my signature.

SAMUEL S. MATTHES.
